US0D1024926S

(12) **United States Design Patent** (10) Patent No.: **US D1,024,926 S**
(45) Date of Patent: ** Apr. 30, 2024

(54) **BATTERY MODULE**

(71) Applicant: **Stryker Corporation**, Kalamazoo, MI (US)

(72) Inventors: **Daniel V. Brosnan**, Kalamazoo, MI (US); **Michael T. Brubaker**, Portage, MI (US); **Ross Timothy Lucas**, Paw Paw, MI (US); **Justin Thomas McLouth**, Portage, MI (US); **Bradley Sommer**, Portage, MI (US)

(73) Assignee: **Stryker Corporation**, Kalamazoo, MI (US)

(**) Term: **15 Years**

(21) Appl. No.: **29/799,144**

(22) Filed: **Jul. 13, 2021**

(51) LOC (14) Cl. **13-02**

(52) U.S. Cl.

USPC **D13/103**

(58) **Field of Classification Search**

(57) **CLAIM**

The ornamental design for a battery module, as shown and described.

DESCRIPTION

FIG. 1 is a front, top, right side perspective view of a battery module;

FIG. 2 is a rear, top, left side perspective view thereof;

FIG. 3 is a rear, bottom, left side perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines in the drawings depict portions of the battery module that form no part of the claimed design.

1 Claim, 9 Drawing Sheets
